UNITED STATES PATENT OFFICE.

KENNETH I. DAVIS, OF LORTON, VIRGINIA.

DESIGN FOR A CIGARETTE HOLDER.

Application filed March 14, 1924. Serial No. 8,925. Term of patent 7 years.

To all whom it may concern:

Be it known that I, KENNETH I. DAVIS, a citizen of the United States, residing at Lorton, in the county of Fairfax and State of Virginia, have invented a new, original, and ornamental Design for Cigarette Holders, of which the following is a specification, reference being had to the drawing forming part thereof.

I claim:

The ornamental design for a cigarette holder as shown.

KENNETH I. DAVIS.
